SLANT ROLLING

Ambrosius Lauer, Karlsruhe, Germany

Application January 9, 1939, Serial No. 249,988
In Germany January 5, 1938

7 Claims. (Cl. 80—12)

This invention relates to a slant rolling process and apparatus for rolling out profiled pieces of hollow bodies which have been produced in a tube rolling, pressing, drawing or other operation.

It is an object of the invention to provide means for changing the shape of hollow metal articles, more particularly of the ends thereof, in a rolling operation and without a mandrel being required.

A special object of the invention is to provide means for contracting hollow metal articles, for example tubular pieces without a mandrel, in a simple and quick operation, in which the formation of folds and undue stresses of the material is avoided and a round product of uniform wall thickness around the center axis is produced.

Still a further object is to provide means by which the distribution of the material of the work piece can be controlled in the desired manner and thickened portions can be produced where required.

A further special object of the invention is to provide means for producing the neck and bottom portions of metal bottles, for instances, steel bottles and similar articles.

With these and other objects in view, as may become apparent from the following disclosures, the invention consists not only of the structures and operations herein pointed out and illustrated by the drawing, but includes further structures and operations coming within the scope of what hereinafter may be claimed.

The character of the invention, however, may be best understood by reference to certain of its structural forms, as illustrated by the accompanying drawing in which—

Fig. 1 is a side elevation, viewed in the direction of the arrow A in Fig. 3, of a roller apparatus having the invention applied thereto, the studs between the bearing plates being omitted.

Fig. 2 is a side elevation of the same roller apparatus, but viewed in the direction of the arrow B in Fig. 3.

Fig. 3 is a plan view of the roller apparatus with the upper bearing plate omitted.

Fig. 4 is a fragmentary sectional view on line IV—IV of Fig. 3 and on a larger scale.

Figs. 5 to 7 are fragmentary axial sections of a work piece to which the method according to the invention has been applied.

Fig. 8 is a similar fragmentary section of the tubular workpiece before the method according to the invention has been applied.

Similar reference numerals denote similar parts in the different views.

Referring now to the drawing in greater detail, the roller head comprises two bearing plates 1 and 2 which are connected by studs 11, Figs. 3 and 4. Rotatably mounted between the said side plates, on shafts 7, 8, 9 and 10, are four inclined profile rollers, viz., two draw rollers 3 and 4 of similar size and two counter draw rollers 5 and 6, roller 5 in this case being shorter than roller 6. The profile which is to be rolled out in this case is the neck of a bottle 11, Figs. 1 and 2 which is held in a chuck 21, Fig. 1. Clamped between the side plates 1 and 2 is a guiding block 12 which is recessed in accordance with the profile shape 15 of the bottle neck to form a mould which serves as a guidance or "fold retaining member" for the bottle neck by which the formation of undesirable folds is prevented in the rolling out operation. The block 12 extends with its upper end through the upper bearing plate 1 and with its lower end into a recess in the lower bearing plate 2 and it may be clamped between the said plates in any suitable manner. As will be seen from the drawing, Figs. 1 and 2, the guide block 12 forms a guidance for the work piece which extends beyond the ends of the smaller rollers 5 and 6 and also beyond the ends of the larger rollers 3 and 4 at both sides. The mould in the guide block is somewhat larger than the shape 30 of the bottle neck which is to be made, but the clearance between the mould in the guide block and the bottle neck is not shown in the drawing. The profile rollers which enclose the bottle neck and serve to roll out the same extend into the mould in the guide block 12, through slots 13, 14, 15 and 16 thereof which, however, are not substantially larger than the portions of the rollers extending therethrough, in order to prevent the material of the work piece from entering into said recesses at the lateral or end edges thereof.

The roller shafts 7, 8, 9 and 10 are mounted in the bearing plates 1 and 2 in a manner to permit adjustment of the inclination of the roller axes. To this end, eccentric bushes may be provided in the bearing plates by rotation or swinging of which through a certain angle the position of the respective shaft in the bearing plate can be adjusted, such an arrangement being shown in Fig. 4 with reference to the shaft 7 of roller 4. As will be seen from this figure, an eccentric sleeve 22 is seated in a bore of the bearing plate 2, and held therein in a fixed position by the pressure exerted upon its flange or collar 5.

23 by a nut 24 screwed on the threaded end portion of the shaft 7 and pressing the collar down on its seat so as to prevent undesirable rotation thereof. The eccentric bore 25 in the sleeve is 5 rounded towards both ends to permit various degrees of inclination of the shaft and a tapered washer 26 is inserted between the nut 14 and the collar 23 in addition to a normal washer 27, to make up for the inclination of the nut with 10 respect to the sleeve. Similarly, spacer sleeves 28 and 29 are provided between the roller 4 and the sleeve 22, the sleeve 28 of which is obliquely cut off at its lower end to engage the sleeve 22 smoothly while sleeve 29 has parallel end faces 15 and serves to define the axial position of the roller 4 with respect to the bearing plate 2. In this manner, lateral and axial displacements of the large draw rollers 3 and 4 by 1 to 5 mm. and more with respect to the lower bearing plate may 20 be effected in order to adjust the rollers in accordance with the profile to be rolled out and to close the mouth piece end of the bottle neck or the bottle bottom, respectively, if desired. The large draw rollers 3 and 4 are provided with 25 cylindrical superfcies portions 20 by which the cylindrical portion 21 of the bottle neck is formed as per Fig. 7.

My novel roller device may be operated by rotating the work piece with respect to a stationary roller device or by rotating the roller device with respect to a stationary work piece.

In the first mentioned case, the chuck 21', Fig. 1, will be rotated in a suitable manner and in the direction indicated by the arrow, and the roller device may be clamped on a base plate 30 while in the second mentioned case, the chuck 21' will be held stationary and the roller apparatus will be rotated by suitable means (not shown). The rollers may be idle running on 40 their shafts for a drive by the relative movement between the roller device and the work piece, but it is also contemplated to provide a positive drive for the rollers, or any of them. To this end, their shafts on which they are fixedly mounted may extend through the lower bearing plate 2, as shown with reference to shaft 7 in Fig. 1, and coupled with a driving shaft 31 by a universal joint or coupling 32 which compensates the inclination of the shaft 7.

50 It will thus be understood from the foregoing that the device operates in this manner that the workpiece 11 which may be in the form of a smooth, cylindrical rolled, pressed or drawn tube as indicated in Fig. 8 is fixedly engaged in a chuck 21' as shown in Fig. 1 and fed with said chuck, by axial movement thereof in the direction of the arrow 33, into the guide block 12, while rotating the chuck in the direction of the arrow 34 relatively to the roller device. The front end of the tube is thus engaged by the portions of the rollers 3, 4, 5, 6 projecting from the slots 16, 14, 13, 15, respectively, and contracted or compressed to the shape shown in Fig. 5. It will be clear that the rolls 3, 4, 5 and 6 are rotated by engagement of the rotating work piece 11 while the roller frame 1, 2 with the bearings for the roller shaft and the guide block 12 remains stationary on the base plate 30.

I have found that by the provision of one or 70 more counter draw rollers 5, 6 of the opposite inclination with respect to the draw rollers 3 and 4, in the manner shown in the drawing, it is possible to control the deformation of the material of the work piece in the desired manner 75 while preserving the uniform wall thickness

around the center axis and the round shape of the work piece. For example, if the draw rollers 3 and 4 have an inclination with respect to the center axis I—I of the roller device of, say 7° and the counter draw rollers 5 and 6 have the same inclination in an opposite direction the material will be concentrated at the bottle neck, in the manner shown in Fig. 5. Now, in a further operation carried out thereafter on the same device or on a second device of similar construction, by adjusting roller 3 to have an inclination of about 8°, roller 5 of 5°, roller 4 of 7° and roller 6 to have an opposite inclination of 3°, the profile shown in Fig. 6 may be obtained. In this case, roller 3 attracts the material, roller 5 retains the material to a certain extent, roller 4 which is less inclined than roller 3 attracts the material somewhat more and roller 6 serves as a counter draw roller for upsetting the material. The profile according to Fig. 6 may then 20 be rolled further to obtain the final shape as per Fig. 7. In this operation, the guiding block 12 which extends beyond the end of the large roller serves as a fold retaining member which prevents the formation of an elliptic cross section 25 of the neck as produced by the known processes. Also, undue stresses of the material folds and cracks therein are avoided and a uniformly thickened wall in accordance with the desired neck shape is obtained, as per Fig. 7. The whole operation takes only a few, for instance 3 seconds. 30

I prefer an arrangement in which each roller is axially subdivided in several sections which may rotate independently and with different speed, in accordance with the different circumferential speeds of the single portions of the work piece. By way of example, roller 3 is shown as composed of three separate sections 37, 38, 39 of different average diameter corresponding to a different speed. The remaining rollers may be 40 similarly subdivided. Thus, undesirable slide-friction between the rollers and the work piece is greatly reduced. The speed difference of the various roller portions relates to both the angular and lineal velocities thereof, since each portion 45 will be imparted the circumferential speed of the portion of the workpiece 11 by which it is engaged, by frictional coupling therewith. Of course, it would be rather complicated in this case to use directly driven rollers although this 50 problem might be solved by special constructions. Anyhow, in the arrangement shown in Fig. 2 the portions 17, 18 and 19 are assumed to be driven by frictional engagement with the workpiece only. 55

It is also contemplated, within the purview of this invention, to provide more than two oblique draw rollers and one or more than two counter-draw rollers which are oppositely inclined with respect to the draw rollers. The rollers may be 60 inclined at any desired angle with respect to each other and two or more rollers may have similar inclinations. Depending on the particular work to be performed on the roller device it is also possible to arrange one or more rollers 65 parallel to the axis I—I of the roller device. The number of draw rollers and counterdraw rollers depends upon the size of the work piece. In case of small diameters, two draw rollers and one counterdraw roller may be arranged, while 70 with larger work pieces two or more draw rollers and two or more counterdraw rollers may be provided, depending on the available space.

My novel roller apparatus is particularly adapted for making the neck or the bottom of 75

steel bottles, but it is also possible to make many other hollow articles, such as, gas containers, by suitable shaping and arrangement of the draw rollers and counterdraw rollers after the principles laid down in the present specification.

I am aware that many further changes may be made and numerous details of construction may be varied through a wide range without departing from the principles of this invention, 10 and I, therefore, do not purpose limiting the patent granted hereon otherwise than is necessitated by the prior art. Slant rolling devices of the general nature of my device are known and disclosed for instance in the U. S. Letters Patent No. 1,665,915 and any features of such known 15 devices may be used in connection with my invention as far as they are suitable therefor.

I claim:

1. An apparatus of the kind specified, for rolling 20 hollow metal articles in a slant rolling operation and without a mandrel, comprising at least two draw rollers which are inclined towards the same side with respect to the axis of the work piece and shaped in accordance with the desired final 25 shape of the article to be produced, at least one roller inclined towards the opposite side and acting as a counterdraw roller, and a guide block forming a mould recessed in accordance with the final shape of the article to be produced, said rollers 30 projecting into the mould in said block, through apertures thereof.

2. An apparatus of the kind specified, for rolling 35 hollow metal articles in a slant rolling operation and without a mandrel, comprising at least two draw rollers which are inclined towards the same side with respect to the axis of the work piece and shaped in accordance with the desired final shape 40 of the article to be produced, at least one roller inclined towards the opposite side and acting as a counterdraw roller, and a guide block forming a mould recessed in accordance with the final shape 45 of the article to be produced and extending at least at one side, beyond the ends of all rollers, said rollers projecting into the mould in said guide block, through apertures thereof.

3. An apparatus of the kind specified, for rolling 50 hollow metal articles in a slant rolling operation and without a mandrel, comprising a frame, at least two draw rollers which are rotatably mounted 55 in said frame in inclined positions towards the same side with respect to the axis of the work piece and shaped in accordance with the desired final shape of the article to be produced, at least one roller rotatably mounted in said frame in an inclined position towards the opposite side and 60 acting as a counterdraw roller, and a guide block fixedly secured to said frame and forming a mould recessed in accordance with the final shape of the article to be produced, said rollers projecting into the mould in said guide block, through apertures thereof.

4. An apparatus of the kind specified, for rolling 5 hollow metal articles in a slant rolling operation and without a mandrel, comprising a frame, at least three rollers rotatably mounted in said frame in differently inclined positions, means adapted to 10 displace the positions of the center axes of said rollers with respect to said frame to adjust separately the angle of inclination of each roller with respect to the center axis of the work piece and a guide block fixedly secured to said frame and forming a mould recessed in accordance with the final shape of the article to be produced, said rollers projecting into the mould in said guide block, through apertures thereof.

5. An apparatus of the kind specified, for rolling 15 hollow metal articles in a slant rolling operation and without a mandrel, comprising a frame, at least three rollers rotatably mounted in said frame in differently inclined positions, means adapted to 20 displace the axial positions of said rollers with respect to said frame to adjust separately the position of each roller with respect to the work piece and a guide block fixedly secured to said frame and forming a mould recessed in accordance with the final shape of the article to be produced, said rollers projecting into the mould in said guide block, through apertures thereof.

6. An apparatus of the kind specified, for rolling 25 hollow metal articles in a slant rolling operation and without a mandrel, comprising at least two draw rollers which are inclined towards the same side with respect to the axis of the work piece and shaped in accordance with the desired final shape 30 of the article to be produced, at least one roller inclined towards the opposite side and acting as a counterdraw roller, and a guide block forming a mould recessed in accordance with the final shape 35 of the article to be produced, said rollers projecting into the mould in said block, through apertures thereof and being composed 40 of a plurality of separate axial sections which are capable of rotation at different speeds.

7. An apparatus of the kind specified, for rolling 45 hollow metal articles in a slant rolling operation and without a mandrel, comprising at least two draw rollers which are inclined towards the same side with respect to the axis of the work piece and shaped in accordance with the desired final shape 50 of the article to be produced, at least one roller inclined towards the opposite side and acting as a counterdraw roller, and a guide block forming a mould recessed in accordance with the final shape 55 of the article to be produced, said rollers projecting into the mould in said block, through apertures thereof, said rollers fitting through said apertures, without any substantial clearance between said rollers and said apertures in an axial direction.

AMBROSIUS LAUER. 60
